UNITED STATES PATENT OFFICE.

JOSEPH OMERZO, OF CHICAGO, ILLINOIS.

RAILROAD-CROSSING GATE.

1,268,050.

Specification of Letters Patent. Patented May 28, 1918.

Application filed August 17, 1917. Serial No. 186,781.

To all whom it may concern:

Be it known that I, JOSEPH OMERZO, a citizen of the United States, residing at Chicago, in the county of Cook and State of Illinois, have invented new and useful Improvements in Railroad-Crossing Gates, of which the following is a specification.

This invention is an automatic gate more particularly adapted for use at railroad crossings where no gatekeeper or guard is provided, and is one operated by the passage of a vehicle over a track through electrically actuating devices.

Most of the crossing gates in common are manually operated and therefore require the attention of a guard for their operation.

Many accidents have occurred at railroad crossings that are unguarded as the expense of maintaining guards at all crossings would be large. The usual means provided for unguarded crossings consists of a warning post with sometimes a bell or other audible signal device.

One object of the invention is to provide a railroad crossing that would be automatically operated by the passage of a train.

Another object is to provide a gate that will be restored to its normal position after the train has proceeded a certain distance from the crossing.

Still another object is to provide a gate with electrically operated devices to automatically actuate the gate to and from its normal position and at the same time give a warning signal.

A further object is to provide track devices including switching mechanisms for controlling the circuits to the electric devices actuating the gate, which track devices are spaced from the crossing suitable distances.

The invention broadly stated comprises a box, a barrier pivotally mounted therein, electric devices for moving the barrier, track devices for controlling the operation of the electric devices, a source of energy, circuits between said source of energy and the several devices and a signal mechanism.

One practical form of construction and assembly will be described and illustrated in the accompanying drawing, in which:

Figure 1 is a side elevation partly in section of the box for the gate actuating devices.

Fig. 2 is an end elevation partly in section of the box.

Fig. 3 is a diagrammatic view showing the circuiting arrangement.

Fig. 4 is an enlarged detail view of the track device operated by the wheel flange.

In the preferred embodiment about to be described the box may be generally indicated at 5 which may be of any usual type and formed of any suitable material. As shown the box is substantially rectangular and is provided with a round top 6. The top 6 has a slot 7 formed therein which extends substantially from the center of the top to one of the sides of the box. Extending transversely of the box is a shaft 8 which is carried in suitable journals indicated at 9 and 10. As shown in Fig. 2 the shaft 8 may be provided with the arms 11 and 12, which arms are provided at their extremities with the counterweights. The arms 11 and 12 may be secured to the shaft in any suitable manner, one means being shown by the pins 15.

Secured to the shaft 8 and between the bearings 9 and 10 is a barrier 16. The barrier may be secured by any suitable means, one of which is indicated by the pin 17. The barrier is preferably so positioned that it will operate freely into the slot 7.

The counterweighted arms 11 and 12 are secured to the shaft and in such a position that they tend to cause the barrier 16 to assume a vertical position. The barrier 16 is provided with a short end 18, which end is provided with a recess for containing a contact brush 19 and a spring 20. The spring 90 operates to force the brush 19 outward. Secured to one wall of the box 5 is a bracket 21, securing means being indicated by the screws 22. The bracket 21 is so formed that it extends for a short distance at right angles to the vertical side of the box and connected to this portion of the bracket is a curved portion 23. As shown the curved portion forms substantially a quadrant.

Secured to the quadrant are segments 24 and 25 which may be formed of any suitable conducting material and are preferably insulated from each other by means of the insulating segments 26, 27 and 28. They are also insulated from the quadrant by means of the insulation indicated at 29. The segment 24 is provided with a terminal 30 and the segment 25 is provided with a terminal 31.

Secured to the shaft 8 at a convenient

point is a gear wheel 32 that is adapted to mesh with the pinion 33 carried upon the shaft 34 of the electric motor 35. The electric motor may be mounted upon the shelf 36 as illustrated. The shelf 36 may be formed as an L-shaped member and is secured to the side wall in any suitable manner, one means being indicated by the rivets 37.

10 The box 5 may have adjacent its base 38 an opening which is closed by the door 39. The opening should be of sufficient size to permit the battery 40 being placed within the box. The battery 40 may be of any desired type but is preferably constructed as a storage battery.

In Fig. 4 there is illustrated one of the track devices the assembly being mounted within the box 41, a suitable switching mechanism is mounted therein and upon a base 42. The base 42 is preferably formed of insulating material and at one end is provided with an upstanding pedestal 43 provided with a transverse hole through which passes a pin 44. Coöperatively connected with the pin is a switch plate formed of the conducting portions 45, 46 and 47 supported by the insulated portions 48, 49 and 50. The free end of the plate is angularly formed as indicated at 51. Mounted upon the base 42 are the spring engaging fingers 52, 53 and 54. At the right hand end of the base 42 there is another pedestal 55 which affords a pivotal mounting for the catch 56. The pivotal mounting being indicated at 57.

The spring 58 may be secured to the base 42 by means of the screw 59. As shown the spring 58 may be formed of a signal leaf and exerts its pressure to force the catch 56 inward toward the switch plate. At a point intermediate of the spring finger 52 and the pedestal 43 is a coil spring 60 which is adapted to be compressed by the downward movement of the switch plate. Secured to the switch plate is a plunger having a stem 61, the lower end of which is connected to the switch plate by means of the pin 62. The upper end of the plunger stem 61 may be provided with a round head 63 so as to provide a battery contact with the flange 64 of the wheel 65. The wheel 65 by means of its tread surface 66 is adapted to ride upon the rail 67. The stem 61 is vertically positioned and is adapted to pass through a suitable aperture formed in the upper wall of the box 41.

Secured to the base 42 and to one wall of the box 41 is an L-shaped member having the vertical portion 68 and a horizontal portion 69. The horizontal portion extends over the switch plate and is provided near its outer end with a suitable hole through which passes the stem 61. Thus two guiding points are provided for the stem. Between the underside of the upper wall of the box 41

and the horizontal portion 69 of the L-shaped member is a coil spring 70. The stem 61 may be provided with a suitable pin or washer as indicated at 71. When the stem 61 is moved downward by the pressure of the flange 64, the spring 70 will be compressed between the pin 71 and the horizontal portion 69. At the same time the switch plate will be moved downward and compress the spring 60. When the switch plate is moved downward a sufficient distance the point 51 will engage with the catch 56 and be held thereby through the action of the spring 58. The catch 56 may be formed of magnetic material or it may carry an armature to coöperate with the core 72 of the electromagnet 73. When the electromagnet 73 is energized it will attract the catch 56 whereupon the energy stored within the spring 60 and 70 will cause the switch plate and plunger to rise and be disengaged from the spring fingers 52, 53 and 54.

Fig. 3 illustrates the circuiting arrangement between the track devices and the barrier actuating devices. The track way is illustrated by means of the rail 67 and 74. The battery 40 has one of its terminals connected to the barrier 16 by means of the conductor 75. Leading from this terminal of the battery 40 is another conductor 76 which is connected to the conductor 77. One terminal of this conductor 77 is connected to the pedestal 43 and to the spring finger 52. The other terminal of the battery 40 is connected to a conductor 78 which is connected to the conductor 79. One terminal of this conductor 79 is connected to the brush 80 of the motor while the other terminal is connected to one terminal of the electromagnet 73. The other terminal of the electromagnet 73 is connected to the conductor 80 which is connected with the segment 25. The spring fingers 53 and 53^a are interconnected by means of the conductor 81 and the spring fingers 54 and 54^a are connected by means of the conductor 82. The conductor 82 is connected to one terminal of the battery 40 by means of the wire 83. The conductor 81 is also connected to the conductor 76 at the point indicated at 84.

Leading from the brush 85 of the motor is a conductor 86 which connects with the spring finger 52. The pedestal 43^a is connected to the conductor 86 by means of the conductor 87. The switch plate conducting portion 46 has connected thereto a conductor 88 which connects with the conducting portion 47^a of the other switch plate. The conducting portion 47 is connected by means of the conductor 89 with the conducting portion 46^a of the other switch plate.

The field 90 of the electric motor 35 has its terminal connected with the conductors 88 and 89. The conducting segment 24 has connected thereto the conductor 91 which is 130

connected to one terminal of the electro-magnet 73. The other terminal of this electro-magnet is connected with the battery 40 by means of the conductor 92 which is connected to the conductors 78 and 83 at the point indicated at 93.

Mounted upon one wall of the box 5 is a circuit closing device 94 which is operated by the barrier 16 when the barrier approaches and is at its lower limit of travel. This circuit closing device 94 may include the audible signal bell 95. As shown in Fig. 3 the circuit 95' for the bell 95 including the circuit closing device 94 is connected to the conductor 75 at the point indicated at 96 and to the conductor 79 where the same is connected with the brush 80.

In practical operation the barrier is normally in the vertical position. Upon the approach of the train the flange 64 will contact with the head 63 forcing the stem of the plunger 61 downward so that the switch plate at the left will engage with its spring fingers and be held in a closed position by means of the catch 56. Thus a circuit will be formed from battery 40, to wires 92, 78 and 79 through motor 35 to wire 86, through contacts 52, switch portion 45 and contact 43 to wires 77 and 76 to the battery. Current is supplied to the field 90 from battery 40 through wires 92, 83 and 82, contact 54, switch portion 47, a wire 89 to field 90 and from said field 90 to wire 88, and switch portion 46 and contact 53 to wires 81 and 76 to battery. Thus the motor is started and the gate lowered. Just before the gate reaches the end of its movement the contact 94 is closed and the alarm sounded through the wire 75 leading from the battery 40, contact 94, alarm circuit 95', wires 79, 78 and 92 to battery. This alarm will continue to sound as long as the gate is in lowered position. When the gate is nearing its lowered position the contact 19 on the gate passes over contact 24 so that a circuit is completed through wires 91 to magnet 73 through wire 92 to battery 40, to wire 75 gate shaft and rear end gate portion 18 back to contact 19 on the barrier or gate. Thus magnet 73 is energized and the catch 56 is actuated to release the switch plate and thus stop the motor with the gate in lowered position. As the train passes over the crossing and proceeds a certain distance therebeyond, the wheel flange 64 will engage with the plunger 61^a of the other track device which will cause the current to flow through the field in the opposite direction as follows: from battery 40, wires 92, 83, and 82 contact 54^a, switch portion 47^a, wire 88 through field 90

to wire 89, switch portion 46^a, contact 53^a, wires 84 and 76 to battery. This will cause the motor to rotate in the reverse direction so as to raise the gate; the current flowing as follows: from battery 40, wires 92, 78 and 79 through the motor to wire 86 and wire 87 to contact 43^a, switch portion 45^a, contact 52^a, wires 77 and 76 to battery. When the gate is raised the contact 94 is broken and the alarm ceases to sound. Near the completion of the upward movement of the gate the contact 19 thereof moving over contact 25 will energize magnet 73^a so as to attract the armature catch and thus release the switch plate and stop the motor with the gate in raised position. The current will flow as follows: from battery 40 wires 92, 78, 79, magnet 73^a, wire 80', contact 25, contact 19, gate shaft, wire 26 and wire 75 to battery.

What is claimed as new, is:—

1. A device of the class described comprising a gate, a reversible motor to operate the gate and having a field coil, normally open, train operated switches on opposite sides of the gate, a circuit for the coil closed by one switch for causing the current to flow in one direction through the coil, another circuit for the coil closed by the other switch for causing the current to flow in the opposite direction through the coil, means for holding said switches closed when operated by the train, an electro-magnet at each switch for controlling said means, circuits for said magnets closed by said gate near the respective limits of its opening and closing movement.

2. A device of the class described comprising a gate, a reversible motor to operate the gate and having a field coil, normally open, train operated switches on opposite sides of the gate, a circuit for the coil closed by one switch for causing the current to flow in one direction through the coil, another circuit for the coil closed by the other switch for causing the current to flow in the opposite direction through the coil, each of said switches including a spring controlled arm having a plurality of insulated portions thereon, contacts co-operating with each portion, said contacts and portions being connected with the circuits, a catch member for holding the arm in closed position when operated by the train, and an electro-magnet controlling said catch member, and circuits for said magnets closed by said gate near the respective limits of its opening and closing movement.

In testimony whereof I affix my signature.

JOSEPH OMERZO.
